UNITED STATES PATENT OFFICE.

IRVING A. FEATHERMAN, OF BROOKLYN, NEW YORK.

PROCESS OF CASTING CORNERS FOR METAL BEDS.

1,416,343.

Specification of Letters Patent. Patented May 16, 1922.

Application filed December 16, 1921. Serial No. 522,796.

To all whom it may concern:

Be it known that I, IRVING A. FEATHERMAN, a citizen of the United States, residing at Brooklyn, in the county of Kings and 5 State of New York, have invented a certain new and useful Improvement in Process of Casting Corners for Metal Beds, of which the following is a specification.

My invention relates to the manufacture 10 of corners for metal beds and has for its object to provide a process whereby the said corners can be formed accurately and so that the surfaces will be true and square with 15 relation to the angles forming the side or foot rails of the bed. These corners are usually formed in castings molded in molders' sand. It is well known that castings formed in this way vary due to the amount 20 of rap given to the pattern by the molder and in addition to the variation in size which is extremely undesirable, there is the further objection that the sides are not true. In devices of this character it is also customary to provide a staple which is adapted to 25 enter an opening in the corner post of the bed, it being then secured by driving a key or passing a bolt through the said staple. It is in the present method of construction difficult to hold these staples true in the 30 casting operation and also there is continual trouble due to the crystallization of the ends of the staple if not the complete melting away of them caused by the molten metal impinging thereon when poured from the 35 ladle. Another difficulty in the casting of the corners is experienced when it is desired to cast them to form a complete frame. In such a case the angle iron which forms one of the bed rails is frequently cast integral 40 with the corner and the angle which extends at right angles thereto is riveted or bolted to the corner which has been cast on the end of the first angle iron. It is extremely desirable to produce these frames so that they 45 are square and so that they will remain so because of the fact that springs are attached to them. It is well known, however, that if one of these frames is dropped and strikes on one of its corners it will be sprung out of 50 a true rectangle into a more or less diamond shape. Numerous attempts have been made to unite the two angle irons at the corner by a single casting operation but without success. This is due to the impossibility of taking 55 the frame out of the mold until it has entirely cooled off because the casting opera-

tion necessarily expands the metal and although the frame can be so that each end is in a different mold all right, it is virtually impossible to take them out without waiting for the molds to cool off. It is, of course, obvious that such a practice would be entirely impractical and not commercially possible. The foregoing, of course, is true only where a chill is employed for a mold, for obviously, it is apparent to persons skilled in the art that it would be impractical to construct such a frame in sand molds.

My invention has for its object to provide a chill which when used renders it possible for one to cast the corners of an entire frame, forming the angle iron rails into a homogeneous mass with the metal from which the corners are formed, and which can be readily and speedily removed from the chill.

Another object of my invention is to provide a chill in which the corners can be cast on the bed rail where a staple is required and in which this staple will not be injuriously affected by the introduction of the molten metal.

For the purpose of illustrating a concrete form for carrying out my improved process I have illustrated in the accompanying drawing a chill which enables the operator to cast the corners uniting both angles by the operation and yet be able to remove the entire frame from the chill and repeat the operation as rapidly as desired.

As shown in the drawings Fig. 1 is an isometric perspective of the complete chill; the angle irons forming the bed rails being shown in dotted lines. Fig. 2 is a sectional view taken on the line 2-2 in Figure 4. Fig. 3 is a sectional view taken on the lines 3-3 in Figure 4. Fig. 4 is a top or plan view of the chill. Fig. 5 is a cross-section taken on the lines 5-5 in Fig. 4. Fig. 6 is a front elevation of the chill. Fig. 7 is an end view of Fig. 6 taken from the end opposite the pivot. Fig. 8 is a top or plan view of a fragmentary portion showing a corner of the frame after the casting is completed. Fig. 9 is a side elevation of the same. Fig. 10 is a perspective view showing how a complete frame is made. Fig. 11 is a sectional view on line 11-11 in Fig. 12. Fig. 12 is an end view of the chill showing the shield for protecting the staple. Figs. 13 and 14 show a modified form of corner.

Similar reference numerals refer to similar parts throughout the entire description.

As shown in the drawings the chill comprises a block 10, which is formed with a base portion 11, and a vertical wall 12, which has pivotally attached to it a top plate 13, which is mounted upon a bolt 14, which extends through the wall 12, and is secured in position by means of a nut 15. The wall 12, is cut away at 16, forming a shoulder upon which a corresponding shoulder 17, formed 5 on the top plate 13, rests. The angle iron forming the rail 18, rests upon the plate 11, its vertical portion resting against the vertical wall formed below the shoulder 16. This shoulder, as clearly seen in Fig. 1 projects 10 outwardly from the wall 12, forming a space intermediate the angle and the vertical part of the wall 12. The top plate 13, is cut away as at 19, so as to provide a recess which will be filled by the molten metal 15 20, which enters through an opening 21, formed at the junction between the top plate 13, and the plate 12, in a position just above the point of union of the two angle irons forming the side and end rails 18 and 25 22. A matrix 23, is placed in the chill on the base plate 11, this matrix being provided with a tapered recess 24, to form the tapered lug 60, which is used to connect the frame of the spring with the corner post of the 30 bed, which is standard construction. The matrix 23, is held from movement by means of a pin 25, which is fixedly mounted in the wall 12, and is further held in position by means of a tongue 26, which extends upwardly 35 from the top of the matrix block 23, and enters into a corresponding recess formed in the top plate 13. The matrix 23, is further secured in position by means of a block 27, which rests against the side of the 40 matrix block 23, its forward corner 28, extending beyond the matrix block and constituting a shoulder which forms a recess in which the metal 29, flows. The face 30, of the block 27, forms a support for the vertical 45 wall of the angle iron 22, which forms the end or side rail, as the case may be, of the frame. The top plate 13, is provided with a downwardly depending portion 31, which is provided with a shoulder 32, the vertical 50 portion of which bears against the face 30, of the block 27, and the horizontal portion rests upon the upper edge of the vertical portion of the angle iron 22, holding it firmly in position, which thus ensures a true 55 and accurate casting. Obviously the downwardly depending portion 31, has its lower wall cut away forming a shoulder 33, which rests against the top and edge of the horizontal portion of the angle iron 22, which 60 further assists in holding it firmly in position. A similar shoulder 34, is formed to receive and hold the horizontal wall and edge of the angle iron 18. The end 35 of the angle iron 22 is cut away to accommodate 65 the end 36 of the angle iron 18 as clearly in-

dicated in Fig. 4 so that they can lay in the same horizontal plane. The downwardly depending portion 31, is also cut away opposite the end face of the matrix 23 so as to form an enclosed chamber into which the molten metal is poured, to form the corners. It will be apparent to persons skilled in the art that there must be four of these chills, one for each corner, which are mounted upon a frame 41, each chill being spaced the proper distance and bolted or otherwise secured in position to form the corners of a frame of the desired size. If the corner was cast with the chill as so far described, the expansion of the metal would be so great 70 that it would be impossible to remove the frame from the four chills until it had cooled off. For while the plate 13 swings in the arc of a circle so that it moves away from the expanded metal, still the matrix 75 expands by the heat absorbed from the molten metal and it and the corner of the metal which bears against the block 23 at the corner 28 and holds the block 23 so tightly it is quite impossible to remove the 80 frame from the chills. I have overcome this objection by providing the block 27, with a mounting which permits it to swing away from the matrix, and, of course, from the metal forming the corner at the shoulder 28. 85 I accomplish this by providing an outwardly extending lug 37, which is fastened fixedly to the face 38, of the block 27, and extends downwardly to a point below the lower wall of the block 27, and is hinged 90 by a pin or pivot 39, to a lug 40, which extends outwardly from the vertical edge 41, of the base 11, and is fixedly attached thereto in any suitable or convenient manner. The center of the pin or pivot 39, is and must 95 be located so that the block 27 will move on an arc of a circle which will take it away from the wall of the matrix block 23, from the moment that it moves upwardly. By providing this swinging movement of the 100 block 27, I find that it is possible to remove the frame even while the metal forming the corners is visibly red hot, so that by following my method of providing a chill, the walls of which are capable of moving away 105 from the metal forming the casting, it becomes possible to cast a frame for metal beds which will be true and accurate at all times and under all conditions.

My means of avoiding the crystallization 110 of the staples when casting the corners to accommodate bed posts is better seen in Figs. 11 and 12.

When casting a corner in this type of chill, I provide a block 70, which is located 115 above the staple 72, so that as clearly seen in the drawing the metal which enters through the opening 71, does not strike upon the staple but strikes upon the block 70, and then flows around it into the chill and fuses 120

125 130

the staple, and the incoming molten metal into a homogeneous mass, but at a temperature which is not great enough to melt off the staples or to crystallize them. By using 5 a chill instead of a sand mold for this purpose it will be apparent to persons skilled in the art that I am able to produce a corner in which all of the surfaces will be true and accurate and the staples can be securely held 10 in proper position. When a corner of the type shown in Figs. 13 and 14 is to be cast, I find it desirable in practice to punch holes in the angle iron 75 in which the staple 72 is mounted. This assists in holding it true 15 and also in fusing it with the angle iron and molten metal.

Having described my invention what I regard as new and desire to secure by Letters Patent is:

20 1. A chill for casting corners for metal beds comprising a base plate, a vertical wall thereon, a top plate pivoted to said vertical wall, a matrix on said base, an angle iron in which is mounted a staple in said chill, 25 and means to shield the staple from the molten metal adjacent its point of entrance.

2. The method of forming a frame for metal beds, the sides and ends of which are formed of angle irons, which consists in 30 notching adjacent ends of said angle irons,

placing said adjacent ends together in a chill mold, one end of which is formed by a matrix, one end and top and one side of which are pivoted to swing away from the frame when moved, flowing molten metal 35 into the mold to unite the frame parts, opening the mold and removing the frame.

3. The method of forming a frame for metal beds, the sides and end of which are formed of angle irons, which consists in 40 notching adjacent ends of said angle irons, placing said adjacent ends together in a chill mold, one end of which is formed by a matrix, one side of which is pivoted to swing away from the frame when moved, 45 flowing molten metal into the mold to unite the frame parts, opening the mold and removing the frame.

4. A chill comprising a base plate, a vertical wall thereon, a top plate pivoted to 50 said vertical wall, a matrix located on said base, a downwardly depending portion on said top plate recessed to form a chamber, a swinging block which holds said matrix from lateral movement and means to hold 55 adjacent ends of angle iron bars within said chamber.

In testimony whereof, I have signed the foregoing specification.

IRVING A. FEATHERMAN.
